UNITED STATES PATENT OFFICE.

HUGO HORNICK, OF CHICAGO, ILLINOIS, ASSIGNOR TO HABER DIE AND STAMPING COMPANY, OF CHICAGO, ILLINOIS, A CORPORATION OF ILLINOIS.

NAME-PLATE-HOLDING MEANS.

Application filed May 21, 1924. Serial No. 714,811.

To all whom it may concern:

Be it known that I, HUGO HORNICK, a citizen of the United States, and resident of Chicago, in the county of Cook and State 5 of Illinois, have invented certain new and useful Improvements in Name-Plate-Holding Means, of which the following is a specification.

My invention relates to improvements in 10 the construction of metal articles, and has special reference to means for attaching plates, such as name plates, on such metal articles as electrically heated flat irons, etc. I devised my invention particularly for securing name or designation plates upon manufactured articles made of sheet metal, though it should be understood that my invention is not thus limited.

Heretofore it has been common practice 20 to secure name plates to such articles by screws or other more permanent fasteners, and where a factory is putting out an article, such as an electric iron, under a single or but a few trademarks or names, such means of 25 fastening is not objectionable. But where, as now frequently happens, such articles are made in large quantities exactly uniform as to construction and are sold under many trademarks or names, the securing of 30 the trade-mark plate in the manner heretofore described is not advantageous. This for the reason that usually the flat irons are shipped in relatively small lots and on short notice, and where numerous trade-mark 35 plates are used it is necessary to carry many irons in stock even though but a few of each trade-mark are carried. If this is not done it is frequently necessary to take off some of the plates and put on others. In some instances this changing of plates amounts to 40 a great burden and adds to the manufacturing cost.

I have devised a system by which the irons are completed except as to the particular 45 plate to be attached. The irons without the plates are placed in stock. Then when an order is received calling for irons with a particular plate the plates are quickly attached to the irons and they are ready to be 50 shipped. My invention is directed especially to a construction which permits the securing of the plates on the irons without screws or other additional fasteners and with a minimum expenditure of both time and 55 effort.

I provide the part to which the plate is to be attached with overlying or overhanging parts, beneath which the plate can be readily inserted, and also with a bendable part or lug adapted to be easily formed 60 over one edge of the plate for locking the plate in position. While my invention is a very simple one, it has great value in the manufacturing and marketing of such metal devices as electric flat irons, etc. 65

In the accompanying drawings forming part of this specification, I have illustrated my invention in connection with an electrically heated flat iron, though it will of course be understood that my invention is 70 not limited to this particular use.

In said drawings:

Figure 1, is a view in elevation of the rear or broad end of an electrically heated flat iron, as it appears before the name plate is 75 applied;

Figure 2, is a vertical section of the iron on the line 2—2 of Figure 1; the heating element not being shown;

Figure 3, is a view similar to Figure 1, 80 showing the name plate secured on the iron;

Figure 4, is a vertical section on the line 4—4 of Figure 3; and

Figure 5, is a detail fragmentary horizontal section on the line 5—5 of Figure 3. 85

In said drawings 1, illustrates the sheet metal shell of an electric flat iron and 2 the heavy cast iron base. The shell is secured to the base by any suitable means, but in any event the rear end 3 of the base projects slightly beyond the rear wall 4 of the shell. It is upon this rear wall 4 that I desire to place the name plate. The name plate 5 is a rectangular plate of sheet metal adapted to have engraved, or otherwise, produced thereon the desired data, names, etc. This plate is preferably smaller in area than said rear wall 4, and I provide means by which one of the plates 5 can be easily, readily and permanently fixed upon said rear wall 4. I provide lugs 6 to overlie or overhang the two ends 7 of the plate 5. As shown, these lugs 6 are struck up out of the rear wall 4 and the plate 5 can be entered beneath these lugs from above and slipped down until the lower edge 8 of the plate rests in contact with some suitable stop or projection, as shown in the drawings, the projecting part of the plate. 95

For the purpose of locking the plate per- 110

manently in position, I provide a bendable lug 9 so arranged that I can readily bend it over the top edge 10 of the plate 5 which, in combination with the lower stop prevents the removal of the plate from beneath the lugs 6. The lugs 6, in order that they may hold the plate 5 close to the back wall 4 are bent to provide just room enough for the plate, and consequently as the plate is inserted beneath the lugs it slides down in contact with the outer face of the rear wall 4. To provide the bendable lug 9 of such material and form, that it can be readily bent over the upper edge 10 of the plate 5, I preferably use a strip of relatively thin sheet metal long enough so that one end will make a tongue 11 projecting upwardly just within the back wall 4, and the other end of which will form the tongue 9 which I first form in contact with the outer surface of said back wall 4, the wall being provided with a narrow slot 12, through which the strip is projected before having its outer end bent upwardly. Even though this strip is quite thin it would prevent the easy insertion of the plate 5 if it projected beyond the outer face of the back wall, and to allow for this I provide the wall 4 with a depression 13 just deep enough to receive the outer end 9 and permit the plate 5 to pass over same. After the plate 5 has been inserted the tongue 9 is lifted out of its depression and is bent outwardly and downwardly over the upper edge 10 of the plate.

I purposely make the depression 13 slightly higher than the projection to permit the easy engagement of the tongue 9 in setting it around the edge of the plate. It should be understood that the strip does not require any other fastening to retain it in place, as the inner end being in contact with the inner face of the wall, it is held tightly in place during and after the bending of the tongue 9. As shown in the drawings, the strip first has a U-shape and then when the tongue is formed over the edge of the plate it has a double U-shape, as the slot 12 is below the upper edge of the plate and consequently there is no possibility of the strip becoming loosened from its holding position, which it might do if the slot 12 were even with or above the edge of the plate. As the strip is made of thin bendable metal the tongue 9 can be readily lifted or bent back if it becomes necessary to remove or exchange the name plate.

As many modifications of my invention will readily suggest themselves to one skilled in the art, I do not limit or confine my invention to the specific details of construction herein shown and described.

I claim:

1. A sheet metal article to which a plate is to be attached, a pair of oppositely disposed struck up lugs for receiving the plate be-

tween them and beneath which the plate can be entered in one direction only, the article provided with a slot adapted to be positioned beneath the plate when set, a bendable strip arranged in the slot and having its ends, one within and one without the article, in contact with the inner and outer surfaces of the article, the plate adapted to be passed over the outer end of the strip while being positioned beneath the struck up lugs, and the outer end of the strip adapted to be bent around and over the adjacent edge of the plate for mutual interlockment in position.

2. A sheet metal article to which a plate is to be attached, a pair of oppositely disposed struck up lugs for receiving the plate between them and beneath which the plate can be entered in one direction only, the article provided with a slot adapted to be positioned beneath the plate when set, a bendable strip arranged in the slot and having its ends, one within and one without the article and in contact with the inner and outer surfaces of the article, the article provided with a depressed portion for receiving the outer end of said strip, to permit the plate to pass readily over same, the plate adapted to be passed over the outer end of the strip while being positioned beneath the struck up lugs, and the outer end of the strip adapted to be bent around and over the adjacent edge of the plate for mutual interlockment in position.

3. A sheet metal article provided with two opposed hooked lugs adapted to overhang opposite edges of a plate to be attached to the article, the article provided with a slot so positioned that the plate will cover same, a bendable strip bent in U-form around the outer edge of the slot, the article provided with a depression extending outwardly from the slot and adapted to receive the outer end of the strip, the outer end of the strip adapted to be formed over the adjacent edge of the plate after the plate has been positioned beneath said lugs, as and for the purpose specified.

4. In an article of the kind described, a sheet metal casing, a base projecting beyond the casing, struck up lugs for overhanging opposite edges of a plate to be attached to the article, the base preventing the escape of the plate from beneath the lugs in one direction, the casing having a slot adapted to be covered by the plate when in position, a bendable strip extending through the slot, its ends extending in a direction away from the plate, both within and without the casing, the outer end of the strip adapted to be formed around and over the overlying edge of the plate, as and for the purpose specified.

In testimony whereof, I have hereunto set my hand, this 26th day of November, 1923.

HUGO HORNICK.
